UNITED STATES PATENT OFFICE.

JAMES QUINLAN, OF MINNEAPOLIS, MINNESOTA.

FUEL-GAS REGULATOR.

Application filed June 18, 1926. Serial No. 116,890.

This invention relates to a gas controlling device, and particularly to such a device adapted to be placed in the gas conduit or line between the consumer's meter and the place of consumption of the gas. It is well known that the gas furnished by the gas companies in cities varies greatly in pressure at different parts of the day, depending upon the amount of gas stored, and other factors. This difference in pressure and also the mal-adjustment of the burners of the consumers results in a large waste or unnecessary use of gas.

It is an object of this invention to provide a simple and efficient device for regulating or controlling the flow of gas to the burners so that the gas will be furnished in proper quantities and efficiently used.

It is a further object of the invention to provide such a device, by means of which a certain volume of gas will be allowed to flow for a certain period, regardless of the pressure on the gas mains.

It is more specifically an object of the invention to provide such a device comprising spaced members extending across the gas supply conduit having therein apertures of different sizes, which apertures are arranged in staggered or reverse relation in the different members, respectively.

These and other objects and advantages of the invention will be fully set forth in the following description made in connection with the accompanying drawings in which like reference characters refer to the same parts throughout the different views, and in which,

Fig. 1 is a view partly in elevation and partly in vertical section, illustrating the device;

Figs. 2, 3 and 4 are views in front elevation, respectively, of the different disk members used in the device; and

Fig. 5 is a view in end elevation as seen from the right of Fig. 1.

Referring to the drawings, a conduit 1 is shown illustrated as a cylindrical pipe or nipple having exterior threads at its ends whereby the same conveniently and easily can be connected in the gas line between the consumer's meter and the place where the gas is burned. The said pipe 1 is also interiorly threaded and adapted to receive therein disks 2, 3 and 4 having peripheral threads thereon so that they readily can be screwed into said pipe and can be adjusted to different positions

therein. The disks 2, 3 and 4 are provided with a plurality of holes 2^a, 3^a and 4^a, respectively, two of such holes being shown in each disk. The disk 2 will be arranged in the pipe most closely adjacent to the meter and the disks 3 and 4 will be spaced slightly from said disk 2 and from each other, as shown in Fig. 1. The holes 3^a in the disk 3 will be at the opposite side of the disk from that in which the holes 2^a in disk 2 are disposed and the holes 4^a in disk 4, will slightly overlap one of the holes 3^a in disk 3. The holes 2^a, 3^a are thus arranged in reverse or staggered relation in the various disks and holes 4^a are slightly out of alignment with holes 3^a.

In operation, a certain number of burners will be turned on and lighted. If desired, all of the burners can be lighted, but preferably, only such number as are most frequently in use, will be lighted. The rate of flow of gas through the meter is then observed. The conduit 1 with the disks 2, 3 and 4 is then inserted in the gas line and the same burners again are lighted. The disks 2, 3 and 4 are adjusted to the proper spacing with the holes in staggered relation so that the burners furnish good flame and so that the flow of gas through the meter materially is reduced. In actual demonstrations, of which many have been made, it has been found that a substantial reduction in the flow of gas through the meter is possible, amounting to 33 1/3% or more. When the disks have been adjusted so as to allow, say two cubic feet per minute to pass through the meter, only this amount will pass through at any time, regardless of what pressure is on in the gas main. In most cities the pressure on the main varies from two feet of water to nine feet of water, the minimum usually being regulated by city ordinance.

With the regulator so installed the burners will operate efficiently to give all the necessary heat and, in fact, in many tests have been shown to give at least forty percent more heat than before the regulator was installed and when more gas was passing through the meter. The disks 2, 3 and 4 can be adjusted closer together or further apart to permit less or more gas, respectively, to pass through the meter, the amount passing through the meter being varied, as desired, and as necessary to furnish the proper supply. Disks 2 and 3, in practice, are arranged almost in contact while disks 3 and 4 are approximately one-eighth inch apart.

From the above description it is seen that

applicant has provided an extremely simple and efficient regulator and one which has a high degree of utility. The device acts as a pressure reducer and regulates the pressure so that the gas passing the device is supplied at a substantially constant pressure. The varying pressure of the gas in the main is thus eliminated from the burners. The strong pressure on the gas forces the same up against 10 the cooking vessels and, together with the induced air current, has a cooling effect on said vessels. By having a constant pressure, this effect is eliminated and the burner also acts more efficiently in consuming the gas. 15 With the use of the device, a material reduction in the quantity of gas used is effected and yet the necessary heat is obtained. As stated, the device has been repeatedly demonstrated in actual practice and is being successfully used in many places.

It will, of course, be understood, that various changes may be made in the form, details, arrangement and proportions of the parts without departing from the scope of applicant's invention, which, generally stated, consists in a device such as shown and described and set forth in the appended claims.

What is claimed is:

1. A device for controlling the flow of combustible gas from a storage supply to the burners therefor comprising a conduit for the gas and a plurality of spaced members extending across said conduit, said members having holes therethrough arranged in staggered relation in the adjacent members, said holes in the respective members decreasing in size toward the supply end of the conduit.
2. A device for controlling the flow of combustible gas from a storage supply to the burners therefor comprising a conduit for the gas, a plurality of spaced adjustable disks therein, each disk having a plurality of holes therethrough of small total cross sectional area compared to the cross sectional area of

said conduit, said holes being disposed adjacent opposite sides of adjacent disks, the holes in respective disks decreasing in size and total cross sectional area toward the supply end of said conduit.

3. A device for controlling the flow of combustible gas from a storage supply to the burners therefor comprising a conduit for the gas, a plurality of spaced adjustable disks therein, each disk having a plurality of holes therethrough of small total cross sectional area compared to the cross sectional area of said conduit, a pair of said disks adjacent the supply end of the conduit being in close proximity and having the holes therein arranged at opposite sides, the disk adjacent said pair in the direction of the gas flow being spaced more widely and having one of the holes therein slightly overlapping a hole in the adjacent disk of said pair.

4. A device for regulating the supply of combustible gas for domestic use, comprising a conduit extending between the gas meter and gas burners and a plurality of adjustable disks in said conduit, each having a plurality of holes adjacent one side and imperforate adjacent the opposite side, said disks being slightly spaced and disposed with said holes adjacent opposite sides of said conduit, the holes in said respective disks being of different size.

5. A device for regulating a supply of combustible gas to a gas consuming means, means comprising a conduit extending to said means and disposed between the gas meter and said means, a plurality of spaced adjustable disks in said conduit, each having a certain number of holes therethrough, the holes in adjacent disks being arranged in staggered relation and said holes in the respective disks increasing in size in a direction away from said meter.

In testimony whereof I affix my signature.

JAMES QUINLAN.
